UNITED STATES PATENT OFFICE.

JOHN L. SUGDEN, OF BUFFALO, NEW YORK, ASSIGNOR TO E. R. THOMAS MOTOR CAR COMPANY, OF BUFFALO, NEW YORK, A CORPORATION OF NEW YORK.

DESIGN FOR A CAP FOR WHEEL-HUBS.

43,085.

Specification for Design.

Patented Oct. 1, 1912.

Application filed August 18, 1911. Serial No. 644,880. Term of patent 7 years.

To all whom it may concern:

Be it known that I, JOHN L. SUGDEN, a citizen of the United States, residing at Buffalo, in the county of Erie and State of New York, have invented a new, original, and ornamental Design for a Cap for Wheel-Hubs, of which the following is a specification, reference being had to the accompanying drawing, forming part thereof.

Figure 1 is a side elevation of the cap for

wheel hubs showing my new design. Fig. 2 is an end view of the same.

I claim:

The ornamental design for a cap for wheel hubs, as shown.

JOHN L. SUGDEN.

Witnesses:

BETTY L. SCOTT,
A. E. DILLON.
